UNITED STATES PATENT OFFICE

2,511,501

VANE TYPE FLUID MOTOR WINDOW
REGULATOR

Burton S. Floraday, Toledo, Ohio, assignor to Detroit Harvester Company, Detroit, Mich., a corporation of Michigan

Application February 18, 1948, Serial No. 9,133

9 Claims. (Cl. 268—125)

1

This invention relates to regulator mechanisms such, for example, as vehicle window regulators, vehicle seat adjusters and convertible top operators, but more particularly to regulators of this type which are pressure fluid operated.

Heretofore, automobile windows have been hydraulically actuated and presently, many automobiles are in use employing hydraulic window regulators. Likewise, tops of convertible automobiles have been hydraulically actuated, it being merely necessary to press a button to render the mechanism operative. Although these mechanisms are to an extent satisfactory and accomplish the purpose intended, nevertheless, they are somewhat delicate and unless manufactured, assembled and installed with care, cause trouble. Furthermore, there is a distinct desideratum to producing a simple and efficient mechanism of this character which is free from the manufacturing, assembling and installing problems inherent in similar existing devices and also one which is relatively inexpensive.

An object is to produce a regulator mechanism which operates in response to pressure fluid which is simple in construction, inexpensive to manufacture on large scale production, can be produced largely from stampings and castings, and which has a minimum of moving parts.

Another object is to produce a hydraulic regulator for vehicle windows and the like, in which use is made in opposite directions of the effective hydraulic pressure.

A further object is to produce a regulator for vehicle windows or the like of the cross arm type in which the motor is arranged substantially in the region of the arm intersection.

A still further object is to produce a new and improved hydraulic regulator assembly which can be mounted as a unit in the door well, for example, and which embodies a hydraulic motor in which efficient use is made of the pressure exerted in both directions.

A still further object is to produce a simple and efficient valve mechanism for hydraulic regulators of the above type which concomitantly renders the motor driven pump effective and admits pressure fluid to effect regulator actuation.

For purposes of illustration but not of limitation, embodiments of the invention are shown in the accompanying drawings, in which

Figure 1 is a side elevation of the front portion of an automobile, parts thereof being broken away to illustrate the window regulator mechanism installed in the front door;

Figure 2 is a side elevation of the rear end por-

Figure 20 is a sectional view substantially on the line 20—20 of Figure 18.

The illustrated embodiment of the invention comprises an automobile 10 of the closed body type, the front half of which is shown in Figure 1 and the rear half in Figure 2. The body has the usual front doors 11 provided with a vertically adjustable window panel or glass 12, the front of which is the usual ventilating glass wing 13. The rear doors 14 of the body are similarly equipped with vertically adjustable glass window panels 15, and disposed rearwardly of the doors 14 are so-called rear quarter glass window panels 16 which are also mounted for up and down movement. In each instance, the vertically adjustable windows have the usual laterally spaced guide channels or strips in which the vertical side edges of the panels slidably engage, such, for example, as indicated by the reference numerals 17 and 18.

As will hereinafter more fully appear, each of the window panels 12, 15 and 16 may be hydraulically actuated in one direction or the other by the simple manipulation of a control instrument such as a lever L conveniently arranged on the inside of the body. The construction and arrangement is such that one window of the system may be moved, for example, downwardly, and simultaneously another window moved upwardly or in the opposite direction, while other windows may remain stationary or in the position of adjustment. Hydraulic pressure for effecting such window movement is supplied by a motor and pump unit P which, as shown, includes an electric motor E electrically connected to a storage battery S through a suitable relay switch. Any suitable pump, such as a gear or Gerotor pump F is connected to be driven by the motor E and associated with the pump F is a reservoir G. Since the details of construction and operation of the unit P form no part of the present invention, further description and illustration is not considered necessary. Suffice it to say that the pump F through a conduit A forces liquid under pressure to the regulator mechanisms associated with the windows to be controlled, and liquid from such regulator mechanisms returns to the pump through a conduit B.

As will hereinafter appear, the conduits A and B may be said to be connected in series with the individual regulator mechanisms. Associated with the several regulator mechanisms, and connected in the return line B are control valve and switch units C respectively operated by the lever L, the arrangement being such that upon manipulation of the lever L in one direction or the other, the electric motor E is energized and a valve directs the flow of liquid under pressure to effect upward or downward movement of the respective window panel. It will be observed that leading from the relay switch on the electric motor E is a line D which extends to the several control units C, either directly or through branch lines, the electrical connection being established by the manipulation of the lever L above mentioned.

As above mentioned, there is associated with each of the vertically movable window panels a regulator mechanism, and this is generally indicated at R. This regulator mechanism may essentially be described as a cross arm regulator equipped at the region of the crossing with a hydraulic motor. An important feature of the motor as will hereinafter be described, is that it makes effective use of the hydraulic pressure in opposite directions so that by means of a small,

compact, and relatively inexpensive device, an exceedingly powerful hydraulic regulator is produced. As shown, the regulator comprises a relatively shallow housing 19 which is sector or semi-cylindrically shaped. Conveniently, the housing may be made by die casting. The rim 20 of the housing is relatively thick to accommodate grooves 21 and 22, the latter being considerably longer and the adjacent ends of the grooves being separated by an imperforate wall 23. The outer ends of the grooves are open to the interior of the housing substantially as indicated on Figure 4.

As noted in cross section, the grooves 21 and 22 are formed with an enlarged shouldered cavity 24, a metal ring 25 seating on the shoulder and a rubber ring or gasket 26 bearing against the top of the metal ring. The shouldered cavity or groove 24 continues as groove 24' in the flat portion of the housing, the gasket 26 being shaped to fit in both grooves 24 and 24'. A cover plate 27 which may be a stamping is bolted to the housing 19 and slightly compresses the rubber gasket 26 to effect a liquid-tight seal.

Associated with the inner end of the grooves 21 and 22 are hollow bosses 28 and 29 respectively, to which hose lines 30 and 31 respectively are connected, thereby to admit liquid under pressure to one or the other of these grooves, and to enable liquid to flow from the housing through the other of these grooves. The location of the hoses or tubes 30 and 31 is not critical but the position as shown is preferable due to the swinging movement of the housing, as will be herein-after explained.

Pivoted concentrically of the arc of the housing 19 is an arm or vane 32 which consists of a stamped metal core 33 and a moldable molded rubber enclosure 34. The core 33 has a hub 35 formed with a polygonal aperture 36 and the peripheral surface of the hub likewise is encased in a moldable rubber sheath 37. It is understood that the term "rubber" includes synthetic rubber and other similar materials having the desired characteristics of resiliency and flexibility to achieve a fluid-tight seal with adjacent surfaces.

Attention is directed to Figure 9 showing the formation of the moldable rubber enclosure or sheath 34. It will be noted that the sheath is provided at opposite sides with elongate flanges 38 extending from the hub of the vane to the outer end thereof which slidably contact or engage the bottom wall of the housing 19 and the cover 27. Intermediate the flanges 38, the sheath is slightly spaced from the adjacent surfaces. Manifestly when the flanges are subjected to liquid pressure, they impinge against the adjacent surfaces to form a liquid-tight seal, but such impingement being in the nature of a line contact is not sufficient to militate against the swinging or rocking movement of the vane. Similarly, the hub sheath 37 is formed with flange projections 39 to effect similar sealing engagement with the flat bottom wall of the housing 19 and the cover 27 respectively.

Also projecting from the periphery of the hub sheath 37 are flanges 40 having V-shaped grooves, three of such flanges being shown, and these serve to effect a liquid-tight seal with the notched portion 19a (Figure 4) of the relatively straight wall portion of the housing 19. It will be recognized that the principle involved in connection with these rubber sealing sheaths is the same as that employed with flexible gaskets used to employ a liquid-tight seal between two rela-

tively moving parts and is well understood by those skilled in hydraulics.

The housing 19 is mounted on a fixed pivot for rocking movements, and as shown, the lower left-hand portion of the housing (Figure 4) is formed with an outwardly extending lug 41 which is rockable upon a pin 42 fixed to and projecting outwardly from a bracket plate 43. The bracket plate 43 is suitably secured within the window well to a convenient door or body panel. Spaced horizontally from the bracket 43 to an adjacent door or body panel, as the case may be, by rivets or screws, is a guide plate 44 formed with an outwardly embossed portion formed with a horizontally elongate guide slot 45, the metal forming the sides of the slot being reversely curved as indicated in Figure 5, to provide a suitable guide for a stud 46 fixed to and projecting laterally from the free end portion of a regulator arm 47, the usual coil spring 48 being interposed between the arm and the guide to hold the parts in the desired position.

The inner end portion of the arm 47 is fixed to an operating shaft 49 which has an intermediate polygonal flange 50 fitting the polygonal opening 36 of the vane 32. Thus it will be manifest that the arm 47 rocks in response to rocking movement of the vane 32. The inner end of the arm abuts against a boss integral with the outer face of the housing 19.

Fixed to the opposite end of the operating shaft 49 is the inner end of an arm 51 which extends in a direction opposite to that of the arm 47. The arm 51 is considerably longer than the arm 47 and carries at its outer end an outwardly extending stud 52 for horizontal sliding movement in a horizontally slotted retainer 53 which is fixed to and depends from a channel member 54 which embraces the lower edge of the window panel 12. The retainer 53 is arranged at one side of the channel 54, and at the opposite side is a somewhat longer retainer 55 which is similarly fixed to the under side of the channel 54 in depending relation. The retainer 55 is similarly formed with a horizontally elongate slot but of somewhat greater length. Mounted for sliding movement in this slot is a stud 56 fixed to the outer end portion of a regulator arm 57. The arm 57 is integral with the stamped metal cover plate 27 and in the raised position of the window panel the arm 57 inclines upwardly and to the right of Figure 4, whereas the arm 51 inclines upwardly and to the left.

From the above description, it will be understood that the regulator unit is virtually a cross arm regulator, a part of the hydraulic motor, i.e. the distance from the operating shaft 49 to the pivot pin 42 constituting one arm, the arm 57 constituting in effect a continuation of such arm and the arms 47 and 51 constituting the other arms of the cross arm regulator. At the juncture of these arms is, in effect, the hydraulic motor which effects the rocking movement of these arms. Thus not only do the arms 47, 57 and 51 rock during window panel actuation, but the motor housing 19 also rocks. This will be understood when it is considered that, for example in Figure 4, liquid under pressure is admitted through the hose 31 to the channel 22. From that channel the liquid enters the housing between the upper side of the vane 32 and the relatively flat housing wall. Hydraulic pressure then operates equally in the opposite direction and imparts counterclockwise movement to the vane 32 and clockwise movement to the housing 19.

19 about its pivot 42. As a result, the arm 51 swings in a counterclockwise direction and the arm 57, which is rigid with the housing 19, swings in a clockwise direction. The arm 47 swings in a counterclockwise direction. Since the movement of the arms is governed by the horizontally elongate guide slots, the result is that the window is caused to move downwardly, the stud on the end of the arm 47 merely riding outwardly along the stationary guide slot 45.

It is important that the proper angular relation of the flat side of the housing with respect to the pivotal mounting 42 be maintained in order that the desired rocking movement of the housing in a direction opposite to that of the vane 32, be effected. Manifestly the hydraulic force exerted against the housing must be in such direction as to cause the housing to rock, and this would not be achieved in certain positions of the flat side of the housing relative to the pivotal mounting.

It will further be understood that at the lower or inner side of the vane 32 (Figure 4), liquid fills the housing and during the swinging movement of the parts as above described, such liquid is forced from the housing through the channel 21 and hose or tube 30. It will be understood that by introducing liquid under pressure through the hose 30, movement of the parts opposite to that above described will be effected, and further description thereof is not considered necessary. Furthermore, since each regulator unit illustrated on Figures 1 and 2 similarly operates, the above description is believed to suffice.

The control unit C which is associated with each of the regulators R for controlling the actuation thereof comprises a mounting plate 58 which is suitably secured to a body or door panel such as 59 (Figure 13). The central portion of the plate is embossed outwardly, and secured thereto by screws 60 passing through apertures in lateral extensions 61 is a valve housing 62 formed with pairs of hose receiving extensions 63 and 64 at opposite sides of the body. A pair of liquid passages is formed in the extension 63 terminating in ports 65 and 66 in the bottom of a valve receiving cavity 67. Likewise in the extension 64 are liquid passages terminating in ports 68 and 69 respectively.

Fitting within the annular cavity 67 is a disc plate 70 having oppositely disposed arcuate or kidney-shaped grooves 71 and 72. The grooves 71 and 72, upon proper movement of the disc 70, may provide a connection or passage between the ports 68 and 65 and simultaneously between the ports 69 and 66. In another position of the disc, the grooves 71 and 72 may respectively establish communication between the ports 65 and 66 and simultaneously a connection between the ports 68 and 69. Formed in the bottom of the disc receiving cavity 67 is an elongate groove 67a which, upon proper positioning of the disc 70, enables communication to be established between the port 68 and the port 66.

The disc 70 is held in desired position by a spring washer 73 which is backed by a plate 74 suitably secured as by a press fit or by staking. The disc 70 has a concentric rectangular aperture to receive the end portion of an operating shaft 75 to which an operating arm 16 is secured. The operating arm 16 is normally held in its neutral or "off" position by a coil spring 77 which is connected at one end to the outer end of the arm 16 and at its other end to a bracket arm 78 projecting outwardly from the mounting plate 51. The inner end of the actuating arm is en-

larged or fan-shaped as indicated at 79 to provide a cam surface 80 in the central portion of which is a notch 81.

Spring urged against the cam surface 80 and normally seating in the notch 81 is a spring-tensioned switch element 82 which forms a part of a switch unit 83 bridging one of the housing extensions 61 and secured as by screws to the mounting plate 58. As indicated on Figure 11, one lead to the switch unit 83 is grounded and the other lead D' connects to the lead or wire D (Figure 1), thereby to energize the electric motor E at any time that the actuating pin 82 is depressed. The arrangement is such that in the intermediate or "off" position of the arm 76, the switch is off so that the electrical circuit is broken. Upon movement of the arm 76 in one direction or the other from its intermediate or "off" position, the cam surface 80 causes the actuating element 82 to be depressed, thereby to render the switch effective for energizing the electric motor E.

The outer end of the actuating arm 76 is connected by a rod or link 84 to the free end portion of a control arm 85 which is fixed to a shaft 86 on the opposite end portion of which is fixed the actuating lever L which is, as above mentioned, arranged on the inside of the door accessible for manipulation.

It has hereinbefore been pointed out that among the advantages of this window regulator system is the feature by which simultaneously one or another window may be actuated in an upward direction, one or more other windows actuated in a downward direction, and still another window or windows retained in the position of adjustment. Thus it will be observed that this system resembles the ordinary hand crank regulators by which several occupants of an automobile may simultaneously open and close their adjacent windows. So far as I am aware, this is a distinctly novel feature in interconnected power operated window regulator mechanisms. The diagrammatic view on Figure 16 illustrates this feature.

In that figure, three regulator mechanisms are schematically shown, referred to generally as R¹, R² and R³. As indicated by the position of the vanes and the respective arrows, the vane in regulator R³ is moving in a counterclockwise direction to move the window to which it is connected in a downward direction. The vane of regulator R² is swinging to the right or in a direction to move the window upwardly toward its closed position. However, the regulator R¹ shows its vane in an intermediate position, indicating that the window is in its midway position and no movement is being imparted to it. It is to be understood that the window movement with respect to regulators R² and R³ is taking place simultaneously.

Considering first the regulator R³, its valve is so positioned that the arcuate groove 71 connects the ports 65 and 66. The port 65 is connected by a tube or hose 31³ to the regulator housing channel 22 and the port 66 is connected by a tube 97 to the port 68' of the valve associated with the regulator R². Liquid under pressure delivered by the pump F through the tube A enters the valve through the port 68 and since the valve groove 72 connects the port 68 with the port 69, liquid then passes from the port 69 to a tube 30³ which communicates with the groove or channel 21 in the regulator R³, thus to cause the vane to swing in a clockwise direction.

Liquid is forced by the vane in regulator R³ 75

from the channel 22, tube 31³, port 65, disc groove 71, port 66 and tube 87 in the valve disc associated with the regulator R². However, this valve disc has been turned or rocked to such position that its groove 72' connects the port 68' with the port 65' so that the liquid under pressure from the regulator R³ then passes to the regulator R² through the tube 31² and through the channel 22 to actuate the vane of the regulator R² in a counterclockwise direction so that upward movement of the window panel associated therewith is effected. The liquid on the right side of the vane of regulator R³ passes therefrom through the channel 21 and the tube 30² and enters the respective valve through the port 69' which is in communication through the groove 71' with the port 66'. The port 66' communicates through a tube 88 with the port 68'' of the valve associated with the regulator R¹. However, this valve unit is in its "off" position in which the valve groove 72'' communicates with the groove 67a which enables liquid under pressure from the tube 88 to pass through the groove 67a to the valve groove 71'' which communicates through the return tube B to the pump F. Thus when the valve is in the "off" position, no liquid under pressure passes to the associated regulator unit since the ports 65'' communicating with the regulator unit through the tube 31 and the port 69'' communicating with the regulator unit through the tube 30 are not uncovered by the valve disc.

As above indicated, movement of the valve disc either to the "down" or "up" positions indicated in Figure 16 will concomitantly, through the connections previously described, render the associated switch unit 83 effective to energize the electric motor E for operating the pump F. However, in the "off" position, the switch is likewise in the "off" position.

In the alternate form shown on Figure 17, the operating arm 76' is electromagnetically operated instead of manually as above described. In this form, electromagnets 89 and 90 have a common armature shaft 91 which carries a sleeve 92 having a pin which rides in a longitudinally elongate slot 93. By energizing the electromagnet 89, the arm 76' is swung upwardly and by energizing the electromagnet 90, the arm is rocked downwardly through the armature 91 and connections described. The electromagnets 89 and 90 are suitably operated by a switch generally indicated at 94, as will be readily understood.

A unitary assembly is shown on Figures 18 to 20, in which a regulator unit as above described may be mounted in its entirety in the window well or other suitable location for window panel movement. The regulator unit R is similar to that above described, so that detail description thereof is not considered necessary. In this form, a metal strip 95 has a pair of spaced outward embossures, and the end portions are secured by rivets 96 to the adjacent door or body structure. In this instance, the stud on the arm 47a rides in a horizontally elongate slot 97 in one of the embossed portions, and instead of the housing being mounted on a fixed pivot, it likewise is provided with a stud 98 carried by an arm 99 rigid with the regulator housing, and which rides in a horizontally elongate slot 100 in the other embossure of the strip 95. The arms 57a and 51a, as above described, have studs riding in horizontal slots or guides in retainers depending from the window edge embracing channel 54a.

A metal strip 101 is disposed in vertical posi-

tion to lie between the outwardly extending embossures, downwardly extending flanges 102 in that region abutting against the strip 95 and being secured thereto by rivets. The ends of the strip are formed with flanges 103 which are secured to the adjacent support by rivets. A vertically elongate guide slot 104 is formed in the strip 101, guidingly to receive a button or stud 105 which is fixed to the regulator R, and in this instance constitutes an integral extension of the operating shaft on which the vane is mounted. It will be manifest that during vertical movement of the window, the slotted strip 101 operates as a guide to cause the window to move in a vertically defined path. It will be apparent that an advantage of this structure is that at the factory, the regulator and its mounting parts can be assembled so that as delivered to the automobile or body company, it is only necessary for the assembly to be located in the desired position and riveted in place. This obviates difficulties caused by improperly locating the regulator mounting plates hereinbefore described. The vertical guide strip militates against binding of the vertical side edges of the window panel in their guides.

Although the regulator mechanism has been described particularly in connection with the actuation of vehicle window panels, it is to be understood that it can advantageously be used for the actuation of other parts which have to and fro movement between two limits of adjustment, such, for example, as automobile seats, tops for convertible automobiles, hoods and rear deck lids. It is further to be understood that numerous changes in details of construction, arrangement and operation may be effected without departing from the spirit of the invention especially as defined in the appended claims.

What I claim is:

1. A regulator for vehicle windows or the like, comprising an hydraulic motor having housing and impeller parts rockable in opposite directions in response to hydraulic pressure, a support, means for rotatably mounting said housing part on said support, lever members operably connected to said parts, and means for operably connecting said lever members to said support and said window for translating the rocking movement of both parts into rectilinear window movement.

2. A regulator for vehicle windows or the like, comprising a support, an hydraulic motor having a housing and an impeller rockable therein about an axis in one direction or the other in response to hydraulic pressure, a pivotal mounting eccentric of said axis pivotally connecting said housing and said support enabling same to rock in a direction opposite to that of said impeller, and working members for translating the rocking movements of the housing and impeller into rectilinear window movement.

3. A regulator for vehicle windows or the like as claimed in claim 2, in which the working members comprise lever arms secured respectively to the housing and impeller, said lever arms having certain end portions operably connected to said window, intermediate portions respectively fixed to said housing and impeller, and other end portions extending beyond said housing and impeller, and guides for causing the other end portions of said arms to move in defined paths generally transverse to the direction of window movement.

4. A regulator mechanism for vehicle windows or the like, comprising a support, a guideway on

said support, a swinging vane swingable about an axis in said housing, a housing enclosing said vane in such manner as to effect a liquid-tight seal between one side of the vane and the opposite side thereof, ports and passages in said housing affording liquid ingress and egress at each of the extreme positions of vane movement respectively, a mounting for the housing enabling rocking movements thereof eccentric with respect thereto, a shaft member for said vane and actuated thereby, and arm means operatively connected to said shaft member and said housing respectively, certain of said arm means being adapted to be operatively connected for window actuation, at least one of said arm means having a member adapted to ride in said guideway aligned with said mounting.

5. A vehicle window regulator comprising an hydraulic motor including a housing, a vane mounted for swinging movement in response to hydraulic pressure within the housing, arms fixed to the vane and to the housing respectively and adapted to connect operatively to a window at the free ends thereof, another arm secured to the vane for movement therewith and extending in an opposite direction from the first arm, an arm portion rigid with the housing and extending in an opposite direction from but in alignment with said first housing arm, a combined mounting and guiding strip having guides, and means connecting the end portions of said last two arms to said guides respectively, said strip being adapted to be secured to a rigid support.

6. A vehicle window regulator mechanism as claimed in claim 5, comprising a combined guide and mounting strip arranged at right angles to and in crossing relation to the other mounting strip, a rigid connection between said strips, an elongate guide in said second mounting strip, and a stud concentric with the hydraulic motor housing in sliding engagement with said elongate guide, said second mounting strip being adapted to be secured to a rigid support.

7. A regulator for vehicle windows or the like, comprising a support, an hydraulic motor having a housing, a rockable part within said housing, bearing means in said housing rockably supporting said rockable part, pivot means eccentric of said bearing means for pivotally mounting said housing on said support, arm means connected to said rockable part for rocking movement therewith, hydraulic actuating means for rocking said rockable part relative to said housing, means for connecting said arm means to said window for actuation of said window, and means for slidably connecting said arm means to said support, whereby both said housing and said rockable part pivot and rock, respectively, in response to hydraulic actuation.

8. In a regulator as claimed in claim 7, further arm means connected to said housing for movement therewith, and means operatively connecting said further arm means and said window for actuation of said window jointly by the respective pivotal and rocking movement of said housing and said rockable part.

9. A regulator mechanism for vehicle windows or the like, comprising a housing, a support, a guideway on said support, a swinging vane swingable about an axis in said housing, said housing enclosing said vane in such a manner as to effect a liquid-tight seal between one side of the vane and the opposite side thereof, ports and passages in said housing affording liquid ingress and egress at each of the extreme positions of vane move-

ment respectively, a mounting for the housing enabling rocking movements thereof eccentric to said axis, a shaft member for said vane and actuated thereby, first arm means operatively connected to said shaft member for movement therewith, second arm means operatively connected to said housing for movement therewith, means for connecting one of said arm means to a window for actuation thereof, and means for connecting the other arm means to said guideway for movement therealong.

BURTON S. FLORADAY.
